UNITED STATES PATENT OFFICE.

SAMUEL HECHLER, OF NEW YORK, N. Y.

TONE-ARM ADJUSTMENT.

1,282,907.

Specification of Letters Patent. Patented Oct. 15, 1918.

Application filed November 2, 1917. Serial No. 199,973.

To all whom it may concern:

Be it known that I, SAMUEL HECHLER, a citizen of the United States, and a resident of the city of New York, borough of Manhattan, in the county and State of New York, have invented a new and improved Tone-Arm Adjustment, of which the following is a full, clear, and exact description.

This invention relates to sound recording and reproducing instruments and has particular reference to tone arm attachments.

Among the objects of the invention is to provide a simple device whereby the counter balancing effect on a tone arm may be easily varied according to various types of records that are being played and without any danger of destroying the musical effect.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a perspective view of a conventional oscillating tone arm having my improvement applied thereto.

Fig. 2 is a vertical sectional view indicating more particularly the relation of my improvement to the known devices.

Fig. 3 is a horizontal section on the line 3—3 of Fig. 2; and

Fig. 4 is a modification of the adjustment means.

Referring now more particularly to the drawings I indicate at 10 a rigid stationary horizontal base having a socket flange 11 in which is fitted the ball portion 12 of a curved tone arm 13 adapted to carry at its smaller or free end any suitable structure or type of sound box 14. These parts are old and well known and illustrated only to show the manner of use or application of my improvement.

The base is provided with a central tubular hub or bearing 15 having a vertical axis in which is journaled a vertical shank 16 of a pivot rod or cross head 17 whose ends are supported in the diametrically opposite side walls of the larger or lower end of the tone arm in any usual or well known manner. A finger piece 18 is rigidly connected

to the cross head and extends rearwardly therefrom and in the same horizontal plane. Since the cross head 17 is supported directly in the lower end of the tone arm it follows that the rotation of the cross head and its shank 16 will always correspond to the rotation of the tone arm around the axis of the hub 15. The shank 16, however, is held in the bearing 16 and hence the cross head constitutes a horizontal pivot provided for the vertical oscillation of the tone arm in practice.

In order to adapt the weight of the free end of the tone arm and the sound box carried thereby to the particular type or make of record being played it has heretofore been proposed to provide an adjustable screw connection for a counter balance spring 19, one end of the spring being attached to the rear end of the finger 18 while the upper end of the spring is connected to one portion of the adjustable screw devices. As ordinarily made, however, the adjustment of the screw cannot be made expeditiously by the average user of the instrument, but only in a shop or by an expert. Furthermore an attempt on the part of the average user to make the adjustment commonly results in the failure of his purpose and even in many cases in the disconnection of the screw connections, rendering the machine inoperative temporarily and calling for expert assistance.

By my improvement I provide a means for not only insuring delicacy of adjustment for the spring 19 so as to suitably counter balance the tone arm at any time but also I provide a quick adjustment whereby the change of the effective weight of the sound box on one standard type of records to another and totally different standard type of records may be made almost instantly by any user and without any danger whatever of disconnecting any part or disabling the instrument. To this end I provide a hollow boss 20 having a vertical axis, said boss being in effect a hollow cylinder extending vertically through the rear portion of the bend of the tone arm and having its axis in alignment with the rear end of the finger 18. The upper end of the boss 20 is a complete horizontal circle except for a notch 21 formed in one side thereof adjacent to which is a shoulder 22. At 23 I indicate a connector extending down through the boss 20 and having the upper end of the spring 19

secured to the lower end thereof at 24. At the upper end of the connector is a head 25 adapted to bear directly upon the upper end of the boss as indicated in Fig. 2 when the effective weight of the sound box is to be increased. A lug 26 extending downwardly from the head 25 parallel to the axis of the connector projects at this time into the notch 21. When the strength of the counter balance spring 19 is to be increased so as to make the effective weight of the sound box less for coöperation with a different type of records, the operator simply lifts up on the connector by grasping a finger piece 27 lifting the lug 26 out of the notch and swinging it around the vertical axis of the connector so as to bring the point of the lug upon the shoulder 22, the connector will be locked until the effective weight of the sound box is to be increased again. It will thus be seen that with the counter balance spring extending between the connector 23 and the finger piece 18 with the proper amount of tension for any standard type of records an adjustment of the spring to any standard type of records may be easily effected by simply manipulating the finger piece 27.

Calling attention now more specifically to Fig. 4 it will be noted that the connector 23 may be in the form of a telescopic screw having a sleeve portion 28 into which the upper threaded end of a bolt 29 is screwed. As indicated the sleeve portion may have a head 30 located within a countersunk open upper end of the head 25 so that by application of a screw driver to the head 30 the effective length of the connector may be increased or diminished for the sake of deli-

cacy of adjustment of the spring at any time, although as above indicated the main adjustment will be effected through manipulation of the finger piece 27 and head 25 which will not disturb the effective length of the connector bolt itself. In other words the delicate adjustment may be made through the rotation of the sleeve 28 independently of the lift of the head 25 and likewise the lifting of the head will not vary the length of the bolt.

I claim:

1. The combination with an oscillating tone arm, a base on which the tone arm is pivoted, and a counter balancing spring acting between the base and the rear portion of the tone arm tending to lift the free end of the tone arm, of a connector between the spring and the tone arm comprising a bolt to the lower end of which the spring is connected, a head secured to the outer end of the bolt, projecting finger means for lifting the head and bolt, and means to hold the head and bolt in elevated position.

2. The combination with an oscillating tone arm, a base in which the tone arm is pivoted, and a counter-balancing spring acting between the base and the tone arm tending to lift the free end of the tone arm, of a connector bolt to which said spring is connected, a head secured to the outer end of the bolt and bearing squarely against the main portion of the tone arm in one position, and having a lug adapted to project against the tone arm when the head and bolt are lifted to increase the tension of the spring.

SAMUEL HECHLER.
